UNITED STATES PATENT OFFICE.

MELVILLE R. BISSELL AND WALTER J. DREW, OF GRAND RAPIDS, MICH.,
ASSIGNORS TO THE BISSELL CARPET SWEEPER COMPANY, OF SAME
PLACE.

CARPET-SWEEPER.

SPECIFICATION forming part of Letters Patent No. 349,684, dated September 28, 1886.

Application filed July 7, 1885. Serial No. 170,923. (No model.)

To all whom it may concern:

Be it known that we, MELVILLE R. BISSELL and WALTER J. DREW, citizens of the United States, residing at Grand Rapids, in the county 5 of Kent and State of Michigan, have invented new and useful Improvements in Carpet-Sweepers, of which the following is a specification.

This invention relates to carpet-sweepers, 10 and has for its objects to provide a novel spring-holder for the drive-wheels, and to provide novel means for discharging the dust-pans.

The objects of our invention we accomplish 15 in the manner and by the means hereinafter described and claimed, reference being made to the accompanying drawings, in which—

Figure 1 is a perspective view of our improved carpet-sweeper in position for use, the bail being turned to one side, thereby locking 20 the dust-discharge and preventing the escape of dirt during the operation of sweeping. Fig. 2 is a side elevation of the sweeper with the brush-casing, which is shown tilted toward 25 one end, thereby opening the dust-discharge for the exit of dirt through the open ends of the dust-pans. Fig. 3 is an end elevation of the sweeper, showing a modification in the 30 form of the dust-discharge lock, the door being partly broken away to show the discharge-opening at the end of one of the dust-pans. Fig. 4 is an elevation of the opposite end of the sweeper, showing the manner of mounting and supporting the drive-wheels. Fig. 5 is a 35 sectional detail showing the manner of attaching the wheel-holder to the brush-casing. Fig. 6 is a perspective view of the spring-wheel holder. Fig. 7 is a partial bottom plan view of the carpet-sweeper. Fig. 8 is a vertical 40 cross-section showing the manner of mounting the rotary brush. Fig. 9 is a perspective view of one of the brush end bearings, and Fig. 10 is a vertical section of the same; Fig. 11, a view similar to Fig. 4, showing the sweeper-case elevated from the floor, as when pressure 45 on the case is removed.

The brush-casing or sweeper-box, designated by the numeral 1, is made in the usual oblong form, and is provided on each side with a dust- 50 pan, 2, that receives the sweepings taken up

by the rotary brush 3, which is journaled in said box. The box sides 4 are extended at one end beyond the end board, 5, and support a cross-bar, 6, to the inner side of which is attached one of the end bearings, 7, for the journals of the brush. This cross-bar 6, in connection with the extended ends of the box sides, also forms a housing for the drive-wheels 8, by which the brush is rotated. The opposite end of the brush is journaled in an end bearing, 7, 55 attached to the inner side of the end board, 9, the other end board, 5, being slotted at 10 for the passage of the brush-shaft.

For the purpose of journaling the rotary brush 3 in such a manner that it will be securely held from any liability of accidental displacement, and yet be readily detachable for cleaning, and also capable of being replaced with ease, we prefer to employ at either or both ends a bearing, 7, formed as shown in Figs. 9 and 10. This bearing plate or lug 7 is provided with openings 11 for the passage of screws by which it is detachably secured in place, and it may also be flanged or ribbed upon the back, or otherwise formed with projections to be countersunk in the surface to which it is attached. The face of this bearing-plate is slightly curved or beveled, as shown, and provided with an open-ended longitudinal slot or groove, 12, at the closed end of which 70 is a depression or seat, 13, for the reception of the brush-journal that is readily slipped therein over the swell or inclined projection 14, adjoining said seat. This form of bearing-plate 75 may be attached to either end of the brush-casing while any other suitable form of bearing-plate may be secured to the opposite end of the sweeper. If desired, however, the bearing-plate 7, constructed as shown in Fig. 9, 80 may be provided for both brush-journals. The brush is readily mounted in position for use by first inserting one of the end pins or journals 85 into its proper bearing-plate, and then crowding the opposite journal past the swell or projection 14 into the adjacent seat 13, the 90 yielding nature of one of the box ends or bearing-supports permitting this to be quickly and easily accomplished, and at the same time 95 serving to insure the retention of the brush in a position where it can rotate freely without 100

liability of becoming dislodged. The brush is removed with equal ease by passing the hand through the bottom of the sweeper-box, grasping the brush-shaft at one end and drawing it firmly outward. We are thus enabled to so arrange the brush that it will be always capable of rotation and instant removal without the employment of attached metal springs, and without any necessity of detaching or otherwise disturbing its bearings.

On the brush-shaft is a friction-gear, 16, through which the brush is actuated by the rubber-faced drive-wheels 8. These drive-wheels are mounted upon a spring-holder, 17, the preferred form of which is shown in Fig. 6, which represents a continuous wire spring capable of supporting both drive-wheels, and at the same time serving as a means for detachably connecting said wheels with the casing, and permitting the casing to have the necessary vertical movement with relation to the wheels to increase or diminish their frictional contact with the brush-gear 16 as required. At each end of the continuous wire spring-holder 17 is an inwardly-projecting axle, 18, for one of the wheels. Extending from the outer portion of each axle the spring-holder rises on an angle to a point above the wheel, then curves inward above the same and toward the casing or sweeper-box, and is bent forward and backward at its respective ends to form the spring-loops 19, whence the opposite ends of the holder pass along the end of the casing 1 to a central inwardly bent loop, 20, that is inserted into a slot, 21, formed in the upper central part of the end board, 5, where it is secured by a covering-plate, 22, that also serves as one of the journal-bearings for the bail 23, to which is attached the sweeper-handle. It is obvious that the form of the spring may be varied without affecting our invention. If desired, the central attaching-loop may be dispensed with and the holder be secured by the plate 22 alone, or by any other convenient means. It will be observed that by this construction pressure downward on the sweeper-casing brings the drive-wheels 8 in closer contact with the brush-shaft and increases the friction; also, by this construction the axles 50 enter the wheels from the outside, allowing the flat surface of the hubs to rest against the end of the casing, and also the spring-holder above the wheels to rest against the box or casing, thus obtaining a firm bearing for the wheels 55 and their spring-holder by simple, inexpensive, and effective means.

In each lower corner of the end board, 9, and communicating with the ends of the dust-pans, is a segmental opening, 24, for the escape of the accumulated sweepings. These openings 24 are closed when the sweeper is in use by an automatic dust-discharge door, 25, that is hinged at its upper portion to the casing end board. This door is provided with a 65 bifurcated latching lever or loop, 26, formed of suitable wire, bent as shown in either Fig. 1 or Fig. 3, and capable of serving as a lock to

secure the door or flap 25 when the bail is thrown into an inclined position to either side of the sweeper-box, as shown in Fig. 1. The latching lever or loop shown in Fig. 1 consists of a wire loop journaled in the upper part of a plate, 27, secured to the end board, 9, and in which one end of the bail 23 is also journaled. This loop extends down centrally over 75 the flap or door 25 and passes through a loop, 28, near its lower edge, where it is held by reason of its length being sufficient to prevent it from slipping out of place either while the door is in motion or at rest. The latching lever or loop shown in Fig. 3 consists of a piece of spring-wire bent twice at a right angle and passed down through small staples or screw-eyes 29, attached to the upper edge of the end board, the lower ends of said wire being passed 85 down partly over the door 25 and secured thereto in any suitable manner. It will be observed that when the bail 23 is thrown in an inclined position to either side of the sweeper-casing, as shown in Fig. 1, it will pass over 90 either arm of the latching lever or loop 26, whichever may be employed, and will thereby automatically secure the door 25 from any liability of opening while the sweeper is in use. By tilting the sweeper toward the exit end of the dust-pans while the bail and handle are in an upright position or at a right angle with the casing, as shown in Fig. 2, the latch or loop 26, being thus relieved of pressure, will permit the door to open and discharge the contents of the dust-pans. It will be seen that the door or flap 25 is thus capable of opening and shutting freely while the bail is nearly or quite at a right angle with the casing, so as not to press against the latching-loop, while 100 by simply turning the bail to either side, as becomes necessary in the act of sweeping, the bail will immediately press against the loop, thereby closing and securing the door, and so preventing the escape of dirt during the operation of sweeping. On one end of the sweeper-box, at the bottom and adjacent to the lower edge of the dust-door, is a runner, 30, that also serves as a brace for the open ends of the dust-pans.

In Fig. 4 the sweeper-case is represented as depressed to its limit, so that it is in contact with the floor and its lower edge in line with the surfaces of the drive-wheels resting on the floor; but, obviously, if the pressure on the case be removed the action of the spring-holder on the wheels will be such as to raise the case from the floor, after which it can be depressed as required.

What we claim is—

1. The combination, with a sweeper-casing, a rotary brush-shaft, and drive-wheels, of a holder for said wheels, consisting of a wire spring, the body of which is arranged at the end wall of the casing and attached intermediate its ends to the said end wall above the brush-shaft, said wire having at each end portion a bent loop and provided at its extremities with axles carrying the drive-wheels,

said casing being capable of yielding vertically in relation to the drive-wheels, to increase or diminish the frictional contact of the wheels with the brush-shaft, substantially as described.

2. The combination, with a sweeper-casing, a brush-shaft, and drive-wheels, of a holder for said wheels, consisting of a continuous wire spring having its body arranged at the end 10 wall of the casing and provided at each extremity with an axle from which it rises at an angle to a point above the wheels, and then extends inward over the latter with portions bent around to form spring-loops, and a plate 15 detachably securing the wire centrally between its ends to the end wall of the casing above the brush-shaft, substantially as described.

3. In a carpet-sweeper, the combination, 20 with the dust-pans and an end board having openings communicating with said pans, of a door hinged at its upper portion to said end board and provided with a latching loop or

lever locked by the bail of the sweeper, substantially as described.

4. In a carpet-sweeper, the combination, 25 with the dust-pans and a casing end board having openings communicating therewith, of an automatic dust-discharge door hinged to said end board and provided with a latch or locking loop, and the sweeper-bail adapted to 30 be turned to either side of the casing, whereby the dust-discharge door is closed and locked by swinging the bail to one side and opened by turning said bail to an upright position and tilting the casing, substantially as described. 35

In testimony whereof we affix our signatures in presence of two witnesses.
